UNITED STATES PATENT OFFICE.

WILLIAM L. SMITH, OF EAST LIVERPOOL, OHIO, ASSIGNOR TO TAYLOR, SMITH & TAYLOR COMPANY, OF EAST LIVERPOOL, OHIO.

DESIGN FOR A PLATE.

41,986.

Specification for Design.

Patented Dec. 19, 1911.

Application filed June 15, 1911. Serial No. 633,445. Term of patent 3½ years.

To all whom it may concern:

Be it known that I, WILLIAM L. SMITH, a citizen of the United States, residing at East Liverpool, in the county of Columbiana and State of Ohio, have invented a certain new, original, and ornamental Design for a Plate, of which the following is the specification, reference being had to the accompanying drawing, forming a part thereof.

The figure of the drawing is a plan view of a plate showing my design.

The plate has an ordinary flat bottom with a peripheral wall rising therefrom at an incline and merging into the inclined rim of the plate, which inclined rim is at an inclination to the bottom less than the inclination of said wall to the bottom.

The plate is divided into receptacles, one

large receptacle of substantially oval-shape and two side receptacles, the latter somewhat crescent-shape, the aforesaid peripheral wall rising from the bottom forming the outer walls of said receptacles, the other walls being formed by a curved partition rising from the bottom and extending across the plate. A cross partition joins the inner wall of the larger receptacle to the rim of the plate and supports the two smaller crescent-shaped receptacles.

I claim:—

The ornamental design for a plate, as shown and described.

WILLIAM L. SMITH.

Witnesses:

EDNA HENDERSON,
ROBT. L. FOUTTS.
